UNITED STATES PATENT OFFICE.

JOHN D. CAMPBELL AND MELLROY E. CUMMINGS, OF PARIS, MAINE; SAID CAMPBELL ASSIGNOR OF ONE-EIGHTH TO FOSTER M. HASKELL, OF BOSTON, MASSACHUSETTS.

DEVICE FOR OPERATING RAILROAD-GATES.

SPECIFICATION forming part of Letters Patent No. 603,621, dated May 10, 1898.

Application filed June 19, 1897. Serial No. 641,402. (No model.)

To all whom it may concern:

Be it known that we, JOHN D. CAMPBELL and MELLROY E. CUMMINGS, citizens of the United States, residing at West Paris, in the county of Oxford and State of Maine, have invented certain new and useful Improvements in Devices for Operating Railroad-Gates; and we do hereby declare the following to be a full, clear, and exact description of the invention, such as will enable others skilled in the art to which it appertains to make and use the same.

Our invention relates to a device for automatically operating railroad-gates by the action of a passing train; and it consists of the mechanism hereinafter described and claimed.

In the accompanying drawings we have shown a device constructed according to our invention, the connection between the operating device and the gate being of a simple character to illustrate its manner of use.

In the drawings, Figure 1 is a general front elevation showing the gate down. Fig. 2 is a plan of the central portion with parts cut away to show the construction of the operating-lever. Fig. 3 is a detail of the beam. Fig. 4 is a side elevation of a modification of the pivoting mechanism of same. Fig. 5 is a plan view of same. Fig. 6 is a section showing modification where a device is used for double tracks, and Fig. 7 is a plan view of same.

The operating device is mounted in a suitable framework A, having a base a resting on supports a^2 . Above the base a is a cross-bar a' , and between them is journaled in a horizontal position the disk G, to which is pivoted the operating-lever H.

The lever H projects horizontally out in such a position that it will be struck by some suitable portion of the train or locomotive, and the disk and lever are joined together by a yielding connection in some suitable manner for the purpose hereinafter shown. As here shown, the lever is pivoted above the disk by means of the same journal which holds the disk, and the two are joined together by means of the springs h h, which connect the two sides of the lever with adjacent edges of the disk.

Above the lever H is a horizontally-disposed beam B, resting on two pivots, one on each

side of the center. As herein shown in Fig. 1, the beam rests on the two pivots C and C', the upper ends of the pivots being formed with knife-edges, which fit into corresponding notches b in the under side of the beam. These pivots are located one on each side of the center, so that the beam is held in stable equilibrium. At the end of the beam are weights D and D', bolted or otherwise secured to the beam, the two weights preferably balancing each other. Connections are made between the disk and the ends of the beam, so that as the former is moved about its center in different directions the ends of the beam will be alternately lifted. This connection is preferably made, as herein shown, by means of cords e and e', each of which connects with the disk at its rear edge and passes around pulleys f or f' and f², being fastened in an eyebolt d or d' in the upper portion of the weights. As the lever H is moved one way or the other one or the other end of the beam is lifted, the opposite end being allowed to fall at the same time.

Connection is made with the gate U, by which the fall of one or the other of the weights D or D' either opens or closes the gate. As here shown, a cord m is secured to one end of the beam and passes over a pulley n to a connection with one edge of a wheel-lever q. The opposite end of the beam is connected in like manner with the opposite edge of the wheel-lever by a cord o, which passes over a pulley p.

Secured to the wheel-lever q is a wheel-lever r, the opposite edges of which are connected with the gate U at points on either side of the pivot by means of cords s and t. The connections are such that the falling of the weight D' raises or opens the gate, and the falling of the weight D lowers or closes it.

In order to retard the fall of the weights, we place beneath the weights dash-pots I and I', having piston-rods i and i', respectively. The upper ends of these piston-rods are pressed normally against the under side of the beam, so as to be always in contact therewith, by means of a cord k and weight l, the cord passing over a pulley k' and being secured to an arm j, secured to the upper end of the piston-rod i or i'. The action of the weight l, which is only just sufficient for the purpose,

keeps the upper end of the piston-rod at all times pressed lightly against the under side of the beam.

In Figs. 4 and 5 we have shown a manner 5 of pivoting the beam so as to steady it laterally. A standard b^2 has upwardly-projecting studs b^4 on each side, so that the beam is held from tilting or swinging laterally. It also has 10 on each side notches or recesses in which fit the pins or pivots b^3 , which pass through the beam. By this construction the beam is more firmly held than as shown in Fig. 1.

In Figs. 6 and 7 we show an arrangement 15 for applying the device to double tracks. The device is set between the tracks, and two levers L and L' are pivoted on a single pivot p and project outward in each direction. The levers are here shown as connected integrally 20 with the disks. Each lever has cords or guides e' connecting with it on opposite sides of the pivot and connecting with one of the weights, as D' , and other cords or guides e in like manner connecting with the other weight, as D . Thus a train on either track going in one 25 direction will exert a pull on the cord e' , operating weight D' , while a train going in the opposite direction will exert a pull on the cord e , operating the weight D .

The operation of our device is as follows: 30 The passing train strikes the lever H and throws it over, lifting one end of the beam bodily from both pivots. This action allows the opposite end of the beam to fall, and in falling it operates the gate, as already described. As the beam descends the notch nearest the lower end strikes its pivot and the lever H having been released by the train the upper weight overbalances the under one and brings the beam to a horizontal position 40 and the lever H to a central position. Thus in whatever direction the train may move the gate is operated and the lever is immediately set again for the next train. The yielding connection between the lever and the disk prevents the blow of the train against the lever from being suddenly transmitted to the weight and so prevents damage.

It will be understood that the operating device is to be set far enough from the crossing 50 so that persons desiring to cross will have due warning, and for this purpose a gong may be attached to the gate in the usual manner.

It will be understood that while the device has been described as applied particularly to 55 railroad-gates it may be applied to other gates, and it may be worked by hand as well as automatically by the passing trains.

It will further be understood that one of 60 these devices is located on each side of each railroad-gate, so that by a train approaching the gate from either direction the gate will be opened, and leaving it from either direction the gate will be closed.

We claim—

65 1. The herein-described device for operating railroad-gates consisting of a pivoted lever adapted to be struck by a passing train,

a horizontal beam weighted at each end, a pair of pivots for supporting said beam, one on each side of the center, mechanism connecting said lever with the ends of said beam for lifting the same alternately by a movement in opposite directions and mechanism connecting the ends of said beam with the gate whereby the latter is opened by the lowering of one end of said beam and closed by the lowering of the other end.⁷⁰

2. The herein-described device for operating railroad-gates consisting of a pivoted lever adapted to be struck by a passing train, 80 a horizontal beam weighted at each end, a pair of pivots for supporting said beam, one on each side of the center, mechanism connecting said lever with the ends of said beam for lifting the same, operating mechanism 85 connecting the ends of said beam with the gate and a dash-pot beneath each end of said beam to retard its downward movement.

3. The herein-described device for operating railroad-gates consisting of a pivoted lever adapted to be struck by a passing train, 90 a horizontal beam weighted at each end, a pair of pivots for supporting said beam, one on each side of the center, flexible cords or guides connecting said lever with the ends of 95 said beam for lifting the same, and flexible cords or guides connecting the ends of said beam with the gate so arranged that the falling of one end of said beam opens and the other closes said gate.

4. In a device for operating railroad-gates, the combination of a disk journaled in a horizontal position, ball-bearings for supporting the same, a lever pivoted to said disk and connected therewith by a yielding connection, a horizontal beam weighted at each end, a pair 105 of pivots for supporting said beam, one on each side of the center, flexible cords or guides connecting said disk with the ends of said beam for lifting the same and mechanism connecting the ends of the said beam with the gate.

5. In a device for operating railroad-gates the combination of a pivoted lever adapted to be struck by a passing train, a horizontal 115 beam weighted at each end, a pair of pivots for supporting said beam, one on each side of the center, mechanism connecting the said lever with the ends of the said beam for lifting said ends, mechanism connecting the ends of said beam with the gate, a dash-pot and a piston and piston-rod therefor beneath each end of said beam for retarding its downward movement and means for keeping said piston-rod pressed upward against the end of said beam.¹²⁰

In testimony whereof we affix our signatures in presence of two witnesses.
